UNITED STATES PATENT OFFICE.

J. WALTER MOORE, OF FORT EDWARD, NEW YORK.

SHOE-SALESMAN'S STOOL.

1,149,391.

Specification of Letters Patent. Patented Aug. 10, 1915.

Application filed January 6, 1912. Serial No. 669,888.

To all whom it may concern:

Be it known that I, J. WALTER MOORE, citizen of the United States, residing at Fort Edward, in the county of Washington and State of New York, have invented certain new and useful Improvements in Shoe-Salesmen's Stools, of which the following is a specification.

This invention relates to shoe-salesmen's stools, and aims primarily to provide a stool of this type equipped with mirrors so arranged that the customer may view both sides and the front of his or her foot so that the appearance of the shoe may be noted after being tried on.

An object of the invention is to so arrange and mount the mirrors that when not in use they may be disposed in position out of the way and in such manner as to be protected against breakage.

A further object of the invention is to so mount that mirror which reflects the front of the shoe that it may be tilted to different angles to enable the customer to note the appearance of the front of the shoe as if looking down upon it from different angles.

For a full understanding of the invention reference is to be had to the following description and accompanying drawing, in which:—

Figure 1 is a view of the stool substantially in top plan looking directly at the foot-rest of the stool. Fig. 2 is a side elevation of the stool. Fig. 3 is a bottom plan view thereof. Fig. 4 is a vertical transverse sectional view on the line 4—4 of Fig. 2. Fig. 5 is a vertical sectional view on the line 5—5 of Fig. 3.

Corresponding and like parts are referred to in the following description and indicated in all the views of the accompanying drawing by the same reference characters.

In the drawings, the stool is illustrated as including, in its structure, a body in the nature of a substantially rectangular frame, the sides of which are indicated by the numeral 1, the rear end by the numeral 2, and the front by the numeral 3.

By referring to Fig. 2 of the drawings, it will be noted that the sides 1 of the frame are inclined downwardly from a point near their rear ends so that the front 3 is located in a lower plane than the back 2. The body-frame 1 is supported at its rear corners by legs 4 and at its front corners by legs 5. The seat for the shoe-salesman is indicated

by the numeral 6 and is supported upon the back 2 of the body-frame and the adjacent portions of the sides 1 thereof. The foot-rest of the stool consists of a board 7 which is secured and supported at its upper portion upon brackets 8 which are in turn secured to the sides 1 of the body-frame and to which the forward portion of the seat 6 is also secured as indicated by the numeral 9. Each of these brackets, as shown, comprises a substantially rectangular shaped plate of metal adapted to be secured to the inner face of the body frame and having at its ends the laterally directed extensions 8 and 9 which project at right angles to the plane of the body member, the plane of the extension 8 being inclined at an angle to the plane of the extension 9 to form a support for the foot rest. The foot-rest lies in an inclined plane between the sides 1 of the frame and has its lateral edges spaced from the said sides so as to accommodate the side mirrors, in a manner which will be presently explained.

For a purpose to be presently explained, a strip 10 is secured to the under side of the foot-rest at each lateral edge thereof and projects part way across the space between the said edge and the adjacent side 1 of the body-frame of the stool, and it will be observed from Fig. 4 of the drawings that each lateral edge of the foot-rest is inwardly beveled as at 11.

Each of the side mirrors is indicated by the numeral 12 and is arranged within a back 13 which is preferably of sheet metal and of substantially oblong form as shown in Figs. 1 and 2 of the drawings. The material of the back is struck out to form hooks 14, located near the ends thereof.

As illustrated in Figs. 2, 3 and 4 of the drawings, the mirrors 12 are slidably disposed between the edges of the foot-rest 7 and the sides 1 of the frame of the stool, and when the mirrors are not in use the hooks 14 engage over the said sides 1 and support the mirrors as shown in Fig. 2 with their backs outermost. In this manner, the mirrors themselves are protected against breakage. When it is desired to so dispose the mirrors that the customer may view his or her foot therein, they are lifted through the space between the foot-rest and the sides of the frame and are tilted to assume about the position shown at the right of Fig. 4. When in such position, the

lower edges of the mirrors will rest upon the projecting portions of the respective strips 10 and their backs will rest against the upper edges of the sides of the frame. In order to prevent complete withdrawal of either mirror from position between the foot-rest and sides of the frame, each mirror is provided at each lower corner with a projecting stud 15 designed to engage with a pin 16 which extends across the said space, and being secured in the foot-rest and the sides of the frame.

That mirror in which the front of the shoe is reflected is indicated by the numeral 17 and is mounted in a suitable backing 18 as in the case of the mirrors 12. Springs 19 are secured at their forward ends to the under side of the foot-rest 7 as at 20 and are coiled as at 21 and are thence extended rearwardly 20 and are pivotally connected with the lower end of the mirror 17 by having their said ends bent laterally and fitted into pintle ears 22 at the said lower end of the mirror. At its upper end, the mirror 17 fits between the upper edge of the foot-rest 7 and the forward edge of the seat 6 and the tendency of the springs 19 is to hold the mirror 17 in elevated position.

A lug 23 is stamped out from the back of the mirror 17 and engages beneath the forward edge of the seat 6 and serves to normally hold the mirror in lowered position. When it is desired to make use of this mirror 17 it is tilted forwardly so as to disengage its lug 23 from the under side of the seat 6, whereupon the springs 19 will act to slide the mirror up between the forward edge of the seat and the rear edge of the foot-rest 7. The upward movement of the mirror 17 is limited by the engagement of the springs 19 against the under side of the foot-rest 7 and by reason of the fact that the mirror has pivotal connection with the rear ends of these springs which may be tilted to assume positions at different angles so that the customer may note the appearance of the shoe from different view points.

Having thus described the invention what is claimed as new is:

50 1. In a stool of the class described, a frame, a foot-rest mounted on the frame and having its side walls inclined downwardly and spaced from the frame, mirrors slidably mounted one between each side of the frame and the adjacent side of the foot-rest, said mirrors having their backs disposed outwardly, means upon each mirror arranged to engage the adjacent side wall of the frame for supporting the mirror in lowered position, and means arranged to support the mirrors in elevated position with said mirrors bearing against the inclined side walls of the foot-rest.

65 2. In a stool of the class described, a frame, a foot-rest mounted thereon, mirrors

slidably mounted one between each side of the frame and the adjacent side of the foot-rest with their backs disposed outwardly when in both raised and lowered positions, stops upon the mirrors adapted to engage the side walls of the frame for supporting the mirrors in lowered position, and means for supporting the mirrors in elevated position.

3. In a stool of the class described, a foot-rest, a mirror slidably mounted at one end of the foot-rest, and a spring secured to the lower face of the foot-rest and pivotally connected to the lower end of the mirror, said spring serving to normally support the mirror in elevated position.

4. In a stool of the class described, a foot-rest, a seat arranged in juxtaposition to the foot-rest and spaced therefrom, a mirror slidably mounted for vertical movement between the foot-rest and seat, a spring secured to the lower face of the foot-rest and pivotally connected with the mirror for normally and yieldably supporting the mirror in elevated position, and means upon the mirror adapted to engage the seat and hold the mirror in lowered position against the tension of the spring.

5. In a stool of the class described, a frame, a foot-rest mounted thereon, and spaced from the sides of the frame, a mirror slidably fitted between each side of the frame and the adjacent side of the foot-rest, means for supporting the mirrors in elevated position, stop pins extending across the space between the sides of the foot-rest and the sides of the frame, and a projection upon each mirror arranged to engage with the adjacent stop pin.

6. In a stool of the class described, a frame, a foot-rest mounted thereon and having its side walls inclined downwardly and spaced from the side walls of the frame, mirrors slidably mounted one between each side of the frame and the adjacent side of the foot-rest, means carried by the mirrors and adapted to engage the frame for holding the mirrors in lowered position, and means mounted on the lower face of the foot-rest and adapted to engage the lower ends of the mirrors for supporting said mirrors in elevated position with the mirrors bearing against the inclined side walls of the foot-rest.

7. In a stool of the class described, a foot-rest, a mirror slidably mounted for vertical movement at one end of the foot-rest, and a spring normally maintaining said mirror in raised position, said mirror being pivotally mounted on the spring and capable of being adjusted to different angular positions with respect to the foot-rest when in raised position.

8. In a stool of the class described, a downwardly inclined foot-rest, a pair of

mirrors disposed one on each side of the foot-rest, a single mirror arranged at the upper end of the foot-rest and between the pair of mirrors, means for normally and yieldably supporting the single mirror in elevated position, and means for holding said single mirror in lowered position.

9. In a stool of the class described, a frame, a foot-rest mounted on the frame and having its side walls inclined downwardly and spaced from the side walls of the frame, mirrors slidably mounted one between each side wall of the frame and the adjacent side wall of the foot-rest, means upon each mirror adapted to engage the adjacent side wall of the frame for supporting the mirror in lowered position, pins extending laterally from the downwardly inclined walls of the foot-rest, studs extending longitudinally from the mirrors and adapted to engage the pins for limiting the upward movement of the mirrors, and clips secured to the bottom of the foot-rest and adapted to bear against

the lower edges of the mirrors for supporting said mirrors in elevated position and in contact with the downwardly inclined edges of the foot-rest. 25

10. In a stool of the class described, a foot-rest, a mirror arranged at one end of the foot-rest and having its lower end provided with pintle ears, coiled springs secured to the lower face of the foot-rest and provided with arms terminating in laterally extending portions fitting in the pintle ears of the mirror, said springs serving to normally and yieldably support the mirror in elevated position, and means for holding the mirror in lowered position against the tension of the springs. 30 35

In testimony whereof, I affix my signature 40 in presence of two witnesses.
